United States Patent Office

Des. 204,726
Patented May 10, 1966

204,726

SAW FRAME

Claude L. David, 703 Broadway, Leipsic, Ohio

Filed May 6, 1965, Ser. No. 85,230

Term of patent 14 years

(Cl. D93—4)

The figure is a perspective view of a saw frame, showing my new design; the undisclosed opposite side being a mirror image thereof.

The broken lines are for purposes of illustration only.
I claim:

The ornamental design for a saw frame, substantially as shown and described.
